MEANS FOR STERILIZING LIQUIDS AND
FILLING CONTAINERS

Henry F. Glunz, Long Island, N. Y.

Application August 6, 1936, Serial No. 94,528

5 Claims. (Cl. 250—49)

The principal objects of the invention are to provide liquids in containers in a sterile condition, so that they may be transmitted to the consumer in a thoroughly sanitary manner entirely free from harmful bacteria or disease germs, and to devise a simple form of apparatus which may be economically operated, and which will concurrently effect the sterilization of the liquid and the placing of same in sealed containers free

5 from contamination.

The principal features of the invention consist in the novel construction of apparatus by means of which the liquid is drawn into a sterilized vacuum chamber through a sterilizing zone and 15 air is concurrently evacuated from containers to permit the sterilized liquid to enter thereinto without contact with contaminating or germ laden air.

The accompanying drawing is a vertical mid-20 sectional elevation of a machine constructed in accordance with this invention.

In carrying this invention into effect the mechanism herein shown is mostly diagrammatic and may be altered in many details.

25 The device as herein shown consists of a base 1 of cylindrical form supporting a central standard in the form of a rigid shaft 2, upon which is mounted a vertical sleeve 3 preferably formed with an externally threaded upper end 4.

30 A cylindrical casing 5 formed with a hollow central boss 6 is threaded on to the threaded upper end of the sleeve 3 for vertical adjustment, the top of the boss being sealed.

The casing 5 is closed at the top by a cover 7, 35 which has a suitable air tight joint therewith. In the center of the cover it is provided with a cylindrical extension 8 over which a cap 9 is fitted and which is air sealed by a friction washer 9'.

40 An exhaust tube 10 is secured in the cap 9 and is adapted to be connected to a suitable vacuum machine to exhaust the air from the casing 5.

A liquid supply tube 11 is mounted in the cap 9 and extends under the cover 7, preferably close 45 to the inner cylindrical wall of the casing 5, and is formed with a broad spreader nozzle 12 adapted to discharge a broad thin sheet of liquid in a downward direction.

Secured to suitable supports on the inner wall 50 of the casing 5 is a shelf 13 arranged immediately below the spreader nozzle 12. This shelf slopes downwardly and inwardly and provides a wide sloping surface, over which a thin film of liquid is discharged by the nozzle 12.

55 Arranged at a suitable distance above the shelf

13 and extending across same is one or more devices 14, preferably mercury vapour lamps of a suitable design which produce rays which have the capability of sterilizing fluids passed therebeneath over the shelf 13 in a thin film. The 5 action of the sterilizing rays is enhanced by the fact that the flowing liquid is attenuated by the presence of the vacuum in the chamber and the liquid is thoroughly sterilized.

If milk is being treated in this apparatus, the 10 passage of a thin film thereof under the ultra violet rays of the sterilizing lamps will have the definite effect of irradiating the same and very materially increasing its vitamin D content.

The sterilized and irradiated liquid flowing 15 over the shelf 13 is discharged into the casing 5 and the height of the level of liquid therein may be regulated by a suitable float controlled valve 15 arranged in the liquid supply tube 11.

The bottom 16 of the casing preferably slopes 20 downwardly from the center boss 6 and a plurality of bosses 17 extend downwardly therefrom adjacent to the periphery. Each of the bosses 17 is bored centrally to house a vertical plunger 18, which is held downward by a coil spring 19, and 25 the lower end of each plunger has a flange 20 with a rubber gasket to engage in sealed contact with the rim of a bottle or other container 21.

Each of the bosses 17 is provided with a vertical duct 22 opening to a tube 23 extending upwardly 30 into the casing 5, and having a port at the lower end opening into the bored recess housing the plunger 18, and the plunger is provided with a duct 24 adapted to open to said port at a predetermined point in the upward movement of the 35 plunger to permit the vacuum in the casing to exhaust the air from the container engaging the plunger flange.

Each plunger has a second vertical duct 25, which communicates with a port at the lower end 40 of a duct 26 in the boss opening to the interior of the casing upon the plunger being moved upwardly to a point where the vacuum duct is closed to permit the flow of the liquid from the chamber 5 into the container under the influence of the 45 vacuum, which will have been created in the container.

It will be understood that by effecting an upward movement of the container against the plunger 18, the air in the container is first exhausted through the registering ducts and tube 23 to a point above the level of the liquid in the casing 5, and immediately thereafter the container is filled with liquid by the suction of the vacuum therein, consequently the liquid will not 55

be contaminated by contact with air which might be germ laden, and the exhausted air is cleared from the top of the tubes 18 without contaminating the liquid in the casing 5.

5 The bottles or other containers are placed on tables or platens 27 supported on vertical plungers 28 mounted in the base structure, and which are operated to lift a predetermined distance by means of a suitable cam 29 engaging a roller contact 30 on the bottom of the plunger 28.

10 A suitable guide 31 is mounted on the center standard to hold the containers in position on the movable platens, allowing free vertical movement thereof.

15 The casing 5 is shown mounted on a threaded support, so that it may be adjusted vertically to suit various lengths of containers to be filled, but other forms of vertical adjustment may be made. So also it will be readily appreciated that 20 the means for lifting the containers may be varied considerably within the scope of the invention.

25 The operation of the process is extremely simple, the casing 5 is sterilized, then the air is evacuated therefrom, the liquid to be treated then flows, under the action of gravity and the vacuum in the casing, through the spreader nozzle over a broad flat surface, and the film being rendered extremely thin by the presence of the 30 vacuum is readily penetrated in its flow by the irradiating sterilizing rays and all germ and bacilli are eliminated. The sterile liquid then falls into the body of the casing, the liquid level being maintained below the irradiating surface 35 by the operation of the float valve.

40 The containers to be filled are sterilized in a suitable manner and fed by suitable mechanism or by hand to the vertically operable tables or platens, and these are operated to raise the containers to engage the valving plungers located in the bottom of the main casing to first effect the evacuation of the air, and then direct the liquid into the vacuumized container and the container is then sealed in any suitable manner.

45 The use of the apparatus described for the sterilizing of liquids and filling of containers involves a special method which forms the basis of a division of this application, filed May 6, 1937, Serial No. 141,047.

50 It will be readily appreciated that the mechanism described may be altered materially without departing from the principal features of the invention herein set forth.

What I claim as my invention is:

55 1. Means for treating liquids and filling containers, comprising a vacuum chamber, a conduit for conducting liquid to the interior of said chamber, means for spreading and supporting the liquid in a thin film at the discharge end of said conduit within the vacuum chamber, means connected with the vacuum chamber and extending above the liquid therein for closing and evacuating air from containers to be filled, and means for directing a flow of the treated liquid 60 from said vacuum chamber to said containers after the air has been evacuated therefrom.

65 2. Means for treating liquids and filling containers, comprising a vacuum chamber, means for directing a flow of liquid to said chamber, said chamber being adapted to contain means for irradiating said liquid as it is discharged into said chamber, a plunger mounted in the bottom of said container having dual passages therein, a passage connecting one of said plunger passages

70 with the interior of the vacuum chamber at the bottom thereof, a passage connecting the other of said plunger passages with the vacuum chamber adjacent to the top and above the liquid contained therein, means for sealing the lower end of the plunger against an open container, and means for operating said plunger to first evacuate the container by connection with the vacuumized chamber and then fill same with the treated liquid by connection below the liquid 10 level of the vacuumized chamber.

75 3. In a means for effecting the sterile filling of containers, the combination of a vacuum chamber for containing a supply of liquid under a vacuumized condition therein, a valve body having ports therein connected to the vacuum chamber one above the level of the liquid therein and the other below the level, a slidably displaceable valve member having sealing co-operation with the container and having ports therein for communicating with the container and so arranged as to register respectively with the ports in said valve body on displacement of the valve member longitudinally to first connect the container interior with the vacuumized interior of the liquid holding chamber to first establish a balanced vacuum in the container and chamber and to thereafter permit the gravity flow of the liquid from the vacuumized chamber into the vacuumizer container.

80 4. Means for treating liquids and filling containers therewith in sterile condition including a supply tank mounted for rotation about a vertical axis and having its interior vacuumized and adapted to retain a supply of the liquid, fluid 35 supply means entering said tank and discharging downwardly adjacent the top thereof, a tray member fixed to the tank and rotating therewith above the liquid level and under said discharge and receiving the latter and spreading 40 the downward discharge laterally and supporting same temporarily within the vacuumized interior of the tank, means for directing irradiating rays downwardly over said rotating shelf and the liquid film supported thereby, and means for 45 evacuating and filling containers with the treated liquid during the rotation of said tank.

85 5. Means for treating liquids and filling containers, comprising a rotatably mounted vacuum chamber, means for directing a flow of liquid to 50 said chamber to be vacuumized therein, said chamber being adapted to contain means for irradiating said liquid as it is discharged into said chamber under the action of the vacuum therein, a series of peripherally spaced plungers 55 mounted in the bottom of said container each having dual passages therein, passages connecting one of said plunger passages with the interior of the vacuum chamber at the bottom thereof, passages connecting the other of said 60 plunger passages with the vacuum chamber adjacent to the top and above the liquid contained therein, means for sealing the lower end of the plungers against open containers, vertically movable table members adapted to each hold a 65 container with its open end in sealing engagement with said plunger and being rotatable with said vacuum chamber, and a cam engaging said vertically movable members to consecutively raise and lower the plungers to effect the consecutive evacuation and filling of the containers and to cut off the liquid flow to the containers and release the same.

HENRY F. GLUNZ.
